UNITED STATES PATENT OFFICE.

FREDERICK N. GARDNER, OF BELOIT, WISCONSIN, ASSIGNOR TO CHARLES H. BESLY, OF CHICAGO, ILLINOIS.

COMPRESSION GREASE-CUP.

SPECIFICATION forming part of Letters Patent No. 737,218, dated August 25, 1903.

Application filed November 80, 1900. Serial No. 38,150. (No model.)

To all whom it may concern:

Be it known that I, FREDERICK N. GARDNER, of Beloit, in the county of Rock and State of Wisconsin, have invented certain new and useful Improvements in Compression Grease-Cups; and I do hereby declare that the following is a full, clear, and exact description thereof, reference being had to the accompanying drawings, and to the letters of reference marked thereon, which form a part of this specification.

This invention relates to compression grease-cups or lubricators adapted for service where heavy lubricants are required.

The invention consists in the matters hereinafter set forth, and more particularly pointed out in the appended claim.

In the drawings, Figure 1 is a view in elevation of a lubricator embodying the salient features of the invention. Fig. 2 is a view in vertical section through said lubricator. Fig. 3 is a plan view of the base. Fig. 4 is a plan view of the nipple side of said base. Fig. 5 is a view, partially in section, of the base and connecting-nipple. Fig. 6 is a view of the compression-cap, illustrating the method employed to prevent the cap from too easily turning on the base.

In general terms the device herein shown as embodying the invention comprises a circular base A, preferably of cast metal, a compression-cap B, having interior screw-threads for engaging exterior screw-threads on the periphery of said base, and a hollow nipple C, secured in the base for the purpose of attaching the lubricator to a bearing or other part to be supplied with lubricant. The said base A has the form of a circular disk provided with a screw-threaded aperture to receive the connecting-nipple C and having on its periphery screw-threads a^1 for engagement with the interior screw-threads of the compression-cap B. The central aperture a^2 of the base is preferably surrounded by a downwardly-projecting boss a^3 . The connecting-nipple C consists of a hollow tube having one of its ends c exteriorly screw-threaded to engage the screw-threaded aperture a^3 of the base A and its opposite or outer end c^1 provided with screw-threads by which it may be inserted and secured in a screw-threaded ap-

erture formed in a bearing or other parts to be lubricated. Between its screw-threaded ends the nipple C is provided with flat sides, faces, or facets c^2 for engagement with the nipple of a tool, such as a wrench, in the act of securing the lubricator as a whole to such bearing or other part. Preferably a shoulder c' is formed between the screw-threaded end c of the nipple, which enters the base A, and the flat-sided or central portion of said nipple, said shoulder bearing against the face of the base A, so as to form a tight joint and aid in holding the nipple firmly and rigid in position with respect to the base. In connecting the nipple and base thus constructed the nipple is preferably first screwed into the base, and the inner end of the nipple, which extends to the top or inner face of the base, is then slightly expanded, upset, or riveted, so as to positively hold the nipple from unscrewing or becoming loose. Such expanding or upsetting of the nipple also serves as a further means of insuring a tight joint between the nipple and the base.

The operation of the device is as follows: The cap is filled with the heavy oil or semi-liquid grease or lubricant commonly used for heavy open bearings and is engaged with the base and screwed thereon, the entrance of the base-plate into the bottom of the cap forcing the grease down through the central aperture of the base to the place where it is desired to apply it. As the lubricant is consumed the cup may be readjusted by screwing it down farther over the base, thereby forcing the lubricant from the cup as occasion may require.

An important advantage is gained by the construction described—namely, one in which the base and nipple are made in separate pieces, and the nipple itself is provided with flat faces for the application of a wrench—for the reason that by this construction the base may be made of cast metal and the nipple of wrought-iron, steel, or other material suitable for giving the necessary strength and durability to the screw-threaded end of said nipple, while at the same time the application of a wrench or like tool used for the purpose of attaching the lubricator to or detaching it from the bearing or other part has no tendency to disconnect the base from the nip-

ple or loosen the joint between these parts, as the force applied by such wrench or other tool comes directly upon the nipple and not at all upon the base A. In other words, the flat-sided part of the device to which the wrench is applied being integral with the screw-threaded part by which the lubricator as a whole is secured to the part on which it is mounted, the torsional strain on the flat-sided part is transmitted directly to the screw-threaded end of the nipple and has no effect on the joint by which the nipple is attached to the body of the device.

As a further improvement in devices of the character above described, the base A is recessed in its upper face or formed with an annular flange a and provided around the margin of said recess with a plurality of holding projections or lugs a', which extend radially inward from said flange. The holding lugs or projections thus formed enable the base to be readily held from rotation while screw-threads are being formed in the central aperture and upon the periphery thereof and while it is otherwise being machined or finished, it being obvious that the presence of such lugs makes unnecessary the use of a chuck or similar holding device and permits the base to be readily and quickly handled, both in the operation of forming the exterior screw-threads and in tapping the central aperture.

As a still further improvement in grease-cups of the character described, the compression-cap B is made or formed of sheet metal of light gage having screw-threads spun or pressed in its cylindrical wall to engage the external screw-threads a' on the periphery of the base. The cap thus constructed of sheet metal is made slightly ellip-

tical in shape, as shown in Fig. 6, by bending the opposite portions of its side wall together. When thus made of elliptical shape, the internal diameter will be approximately the same as the external diameter of the base, so that it may be easily forced over the circular periphery of said base. The strain brought upon the side wall by its distortion from its normal or elliptical shape in the act of placing it upon the base causes the cap to grip the opposite sides of the base with yielding or spring pressure. The cap is made of such size that it will be forced into circular form by the base when it is placed on the latter and will fit the screw-threads of the base so tightly as to prevent the escape of grease at any point in the circumference of the base. Such pressure of the cap upon the base also serves to hold the cap in position to which it is adjusted by the friction resulting from such pressure and prevents the cap being shaken or jarred out of position by the jarring of moving machinery with which the lubricator may be connected.

I claim as my invention—

A compression grease-cup, comprising a circular base having its perimeter screw-threaded, and a sheet-metal screw-threaded compression-cap made slightly elliptical to afford yielding pressure of its opposite side portions against the said base.

In testimony that I claim the foregoing as my invention I affix my signature, in presence of two witnesses, this 7th day of November, A. D. 1900.

FREDERICK N. GARDNER.
